CLAIM

The ornamental design for a puzzle board as shown and described.

DESCRIPTION

FIG. 1 is a front, top, and left perspective view of a puzzle board showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is a perspective view of the Puzzle Board in a folded upright position; and,

FIG. 10 is a perspective view of the Puzzle Board in an unfolded flat position with the drawers opened.

The broken lines shown in the drawings represent portions of the puzzle board that form no part of the claimed design.

1 Claim, 10 Drawing Sheets
